(57) **CLAIM**

The ornamental design for a carrying handle, as shown and described.

DESCRIPTION

FIG. 1 is a perspective view of a carrying handle that incorporates my new design.

FIG. 2 is a top view thereof.

FIG. 3 is a front view thereof. A rear view thereof is identical to the front view shown in FIG. 3.

FIG. 4 is a left-side view thereof. A right-side view thereof is identical to the left-side view shown in FIG. 4; and, FIG. 5 is a bottom view thereof.
